(57) **CLAIM**

The ornamental design for a solar car port double as shown and described.

DESCRIPTION

FIG. 1 is a rear elevational view of our design in a first orientation.

FIG. 2 is a perspective view thereof.

FIG. 3 is a rear elevational view of our design in a second orientation.

FIG. 4 is a perspective view thereof.

FIG. 5 is a rear elevational view of our design in a third orientation.

FIG. 6 is a perspective view thereof.

FIG. 7 is a rear elevational view of our design in a fourth orientation.

FIG. 8 is a front elevational view thereof.

FIG. 9 is a left-side elevational view thereof.

FIG. 10 is a perspective view thereof.

FIG. 11 is a right-side elevational view thereof; and,

FIG. 12 is a top plan view thereof.

Broken lines show portions of the solar car port double that form no part of the claimed design.

1 Claim, 6 Drawing Sheets
